UNITED STATES PATENT OFFICE.

THOMAS M. DUDGEON, OF CRAFTON, PENNSYLVANIA, ASSIGNOR TO PITTSBURGH STOVE AND RANGE COMPANY, OF PITTSBURG, PENNSYLVANIA, A CORPORATION OF PENNSYLVANIA.

DESIGN FOR A BASKET-GRADE.

SPECIFICATION forming part of Design No. 36,052, dated September 9, 1902.

Application filed July 29, 1902. Serial No. 117,572. Term of patent 7 years.

To all whom it may concern:

Be it known that I, THOMAS M. DUDGEON, a citizen of the United States, residing at Crafton, in the county of Allegheny and State of Pennsylvania, have invented a new, original, and ornamental Design for Basket-Grates, of which the following is a full, clear, and exact description, reference being had to the accompanying drawings, forming part hereof, in which the invention is illustrated in perspective view.

The leading features of the design consist of a front frame, comprising cross-bars at the top and bottom, each twisted at each side of the center and connected at the center between the twisted portions by an upright twisted bar and at the ends by twisted corner-posts. Near the tops and bottoms of the corner-pieces are spherical portions, the corner-posts and cross-bars apparently extend-

ing through the spheres and protruding from the sides thereof. At the bottoms the corner-posts are split, forming divergent feet or supports. Between each corner-post and the twisted center upright is an open-work formation having the appearance of reversely-extending spiral scrolls, the volutes of the spirals being suitably connected. 25

The back frame of the grate is a duplicate of the front frame, the two being connected by side frames, as shown. 30

I claim—

The ornamental design for a basket-grate as herein shown and described.

In testimony whereof I have hereunto set 35 my hand.

THOMAS M. DUDGEON.
